UNITED STATES PATENT OFFICE.

WILLIAM LESTER MCKNIGHT, OF ST. PAUL, MINNESOTA, ASSIGNOR TO MINNESOTA MINING AND MANUFACTURING COMPANY, OF ST. PAUL, MINNESOTA, A CORPORATION OF MINNESOTA.

HAND BLOCK FOR ABRASIVES, ETC.

Application filed November 14, 1922. Serial No. 600,831.

To all whom it may concern:

Be it known, that I, WILLIAM LESTER MCKNIGHT, a citizen of the United States, and a resident of St. Paul, in the county 5 of Ramsey and State of Minnesota, have invented certain new and useful Improvements in Hand Blocks for Abrasives, Etc., of which the following is a specification.

This invention relates broadly to supporting and sustaining means, more particularly to an improved hand block for supporting and sustaining a sheet of abrasive material or the like, and especially one characterized by the feature of retaining such sheet by the pressure of the hand grasping the block and for tensioning the sheet relatively to the block when in use, together with certain other features to be pointed out hereinafter.

While this invention, for the sake of convenience, is illustrated as embodying a hand block adapted for carrying an abrasive sheet or for otherwise having an abrasive element associated therewith, it will be readily understood that the block as illustrated may be employed for other similar purposes, or may be embodied in combination with other mechanism as will occur to those skilled in the art, and therefore this invention finds a wide field of utility for other purposes than the specific ones herein discussed.

The principal objects and advantages which characterize this invention reside in the provision of improved means for carrying and sustaining an abrasive element; the provision of improved flexible means for carrying and sustaining an abrasive element; the provision of improved means for carrying and sustaining a sheet of abrasive material; the provision of improved flexible means for carrying and sustaining a sheet of abrasive material or the like; the provision of an improved hand block for carrying and sustaining a sheet of abrasive material or the like, or one adapted for having an abrasive element otherwise applied thereto; the provision of a compressible and flexible hand block for carrying and sustaining a sheet of abrasive material or the like, or one adapted for having an abrasive element otherwise applied thereto; the provision of an improved hand block for carrying a sheet of abrasive material or the

like and characterized by the features of 55 proper weight, flexibility, if desired, and shape rendering it convenient to be grasped for use; the provision of an improved hand block for carrying and sustaining a sheet of abrasive material or the like, characterized 60 by the provision of sheet engaging means actuated by the grip of the hand; the provision of an improved hand block for sustaining a sheet of abrasive material or the like, characterized by the provision of 65 hand-pressure actuated sheet engaging means; the provision of an improved hand block for sustaining a sheet of abrasive material or the like, characterized by the provision of means for tensioning the sheet 70 relatively to the block by the application of manual pressure to the latter; the provision of an improved hand block characterized by the embodiment integrally therewith of hand-pressure actuated sheet 75 engaging means; the provision of an improved hand block for sustaining a sheet of abrasive material or the like, characterized by the embodiment therein of hand-pressure actuated sheet engaging means and further 80 characterized by feature of flexibility; the provision of an improved hand block for sustaining a sheet of abrasive material or the like having means for tensioning the sheet relatively to the block by the application of manual pressure to the latter, such block being further characterized, if desired, by the feature of flexibility; the provision of an article of the character described that is highly efficient in operation, permits the user to manipulate the sheet of abrasive material without bringing his hands in contact with the surface being treated, or with the abrasive material, and which article may be manufactured at low cost; together with certain further objects and advantages which will hereinafter be pointed out or appear.

This invention is further characterized by the provision of a structure which may be produced in one of several ways, and, therefore, as this description proceeds, I will embody therein brief references to certain alternate preferred methods for making the device of this invention.

The foregoing and such other objects and advantages which may appear or be pointed out as this description proceeds are attained

in a structural embodiment illustrated in the accompanying drawing, in which:

Figure 1 is a perspective view of the device of this invention ready for use;

5 Figure 2 is a horizontal sectional view of the device of Figure 1 taken on a horizontal plane indicated by the dotted line A;

Figure 3 is a side elevation of the device of this invention illustrating the manner of 10 applying a sheet of abrasive material or the like thereto; and

Figure 4 is a side elevational view illustrating one of the functions carried out by this invention.

15 Referring more particularly to the drawings, and first to Figures 1 and 2, I provide a block 5 preferably substantially rectangular in contour and having the plain surfaces 6 and 7, which, for convenience, I shall refer 20 to as the bottom and top surfaces. The end faces 8 and 9 of the block are conveniently perpendicular with respect to the surfaces 6 and 7 and the sides 10 and 11 are similarly conveniently perpendicular to the top and 25 bottom surfaces.

In the form of the invention shown in Figure 1 the body of material for forming the block 5 may be of rubber or any other flexible material, although if desired, the 30 block may be made of a compressible or even of a rigid material. However, I shall, in describing the block, assume that the same is made of rubber, preferably a relatively stiff rubber yet sufficiently flexible for the 35 purpose.

The block 5 includes the means for gripping the end portions 12 and 13 of an abrasive sheet 14, said sheet being engaged against the supporting surface 6 and such 40 gripping means preferably comprising sinuated slots or recesses 15 and 16 cut or otherwise formed in the ends of the block and disposed generally in planes above the horizontal longitudinal axes of the block so that 45 resilient tongues 17 and 18 are afforded. The slots 15 and 16 extend from the opposite end walls 8 and 9 toward the center of the block but terminate a sufficient distance from each other so as not to materially 50 weaken the construction.

It will be observed here that in forming the slots 12 and 13 they may be formed by sawing, the cut thus made by a saw being entirely sufficiently large to accommodate 55 a piece of sand paper or the like.

The following method, however, may be employed in making the device shown in Figure 1 and also employed where it is desired to make the body 5 carrying the surface 6 of hard rubber and the upper portion 60 of the block of soft rubber so as to afford the flexible tongues 17 and 18 (or conversely): that is to say, the bottom section 5 is molded to afford the sinuated surfaces 19 and 20 shown in Figure 2, and these sur-

faces may include transverse and longitudinal corrugations 21 and 22, respectively. The upper section of the block carrying the tongues 17 and 18 is then molded and provided with complementary surfaces to those 70 designated 19 and 20. The upper section is then placed upon the lower section and the two either vulcanized or cemented together along the dotted line A.

By this arrangement it will be observed 75 that the lower section of the block may be made of hard rubber and the upper section of soft rubber, or vice-versa, or both sections may be made of rubber of the same consistency. Furthermore, the degree of flexibility of the material of which the block is formed, rubber or any other suitable material, may be varied to suit the requirements 80 of the use to which the article is to be put.

Another feature which is worthy of mention here is that especially when applied to a machine, for which the invention finds utility, the sections of the block formed by the method outlined above may be made entirely separate and connected by a rivet 85 or suitable detachable fastening means, which permits replacement when desirable.

It is to be observed that when the operator grasps the block the corrugated surfaces of the slots 12 and 13 serve to firmly 95 engage the ends of the sheet interposed therebetween and by compression tend to shorten the sheet and thus tension its portion 14 on the surface 6. This will especially take place where a very thin sand or 100 emery paper is used and in actual practice has been found to possess a high degree of efficiency and utility.

Upon reference to Figure 4 it will be perceived that where the abrasive material is 105 employed in polishing a curved surface 23, the block 5 may be caused to flex and take the form of the surface to which it is applied and thus insure that an accurate and smooth application of the abrasive material 110 is attained.

The view shown in Figure 3 serves to illustrate the manner of applying the abrasive sheet to the block, this being accomplished by placing the block on the sheet and lifting the end tongues 17 and 18 a sufficient distance to permit insertion of the ends 12 and 13 of the sheet. When the ends of the sheet are inserted the tongues are released and returned to the position 115 shown in Figure 1.

Having thus described my invention and illustrated its use, what I claim as new and desired to secure by Letters Patent is:

125 1. In a device of the character described, in combination, a block having complementary sinuated recesses in its opposite ends, and an abrasive element embracing one surface of the block and engaged in said recessed ends.

2. In a device of the character described, in combination, a flexible block having sinuated recesses in its ends, and an abrasive element embracing one surface of the block and engaged in said recessed ends.
3. In a device of the character described, in combination, a solid flexible body having flexible tongues spaced therefrom, and the portions of said body adjacent said tongues being corrugated.
4. In a device of the character described, in combination, a solid flexible body having flexible tongues spaced therefrom, and the surfaces of said body adjacent said tongues, and said tongues being corrugated.
5. In combination, a flexible body having flexible tongues spaced therefrom, said body being provided with transversely and longitudinally corrugated surfaces adjacent to said tongues, and a flexible abrasive sheet having its ends between said tongues and said corrugated surfaces.
6. A supporting and retaining device for abrasives and the like which includes a continuous flexible block provided with recesses in opposite ends thereof, the complementary portions of the block formed by
7. A supporting and retaining device for abrasives and the like which comprises a continuous flexible block provided with recesses in opposite ends thereof, an abrasive sheet having its ends in said recesses the flexibility of the material of said block when pressure is applied thereto causing the parts of the block adjacent said recess to frictionally engage and retain said sheet upon the block.
8. In a device of the character described, a hand block for sustaining a sheet of abrasive material, having an integral part thereof formed as means for engaging said sheet, said means being actuated by the pressure of the hand to increase the securing of the sheet on said block, said means being rendered substantially inactive and permitting removal of the sheet upon release of the pressure of the hand.
- In testimony whereof I have hereunto signed my name.

WILLIAM LESTER McKNIGHT.
